UNITED STATES PATENT OFFICE

158,059

LOUNGING CHAIR

Lodovico Favilla, Boston, Mass.

Application May 23, 1949, Serial No. 2,814

Term of patent 14 years

(Cl. D15—1)

To all whom it may concern:

Be it known that I, Lodovico Favilla, a citizen of the United States, residing at Boston, in the county of Suffolk and State of Massachusetts, have invented a new, original, and ornamental Design for a Lounging Chair, of which the following is a specification, reference being had to the accompanying drawing, forming part thereof.

Figure 1 is a perspective view of a lounging chair in an upright position showing my new design, and

I claim:

The ornamental design for a lounging chair, as shown.

LODOVICO FAVILLA.
